US00D536410S

(12) **United States Design Patent** (10) Patent No.: **US D536,410 S**
(45) Date of Patent: **** Feb. 6, 2007**

(54) **PLAYGROUND EQUIPMENT**

(75) Inventors: **Stephen F. Nye**, Syracuse, UT (US);
Kyle Smith, Layton, UT (US); **Jeremy Evans**, Plain City, UT (US); **Jacob Kearl**, Plain City, UT (US)

(73) Assignee: **Performance Design, Inc.**, Clearfield, UT (US)

(**) Term: **14 Years**

(21) Appl. No.: **29/255,201**

(22) Filed: **Mar. 6, 2006**

(51) LOC (8) Cl. **21-03**

(52) U.S. Cl. **D21/822**; D21/823; D21/826

(58) Field of Classification Search D21/811, D21/814, 818-827; 482/35, 36; 472/116-125

See application file for complete search history.
